UNITED STATES PATENT OFFICE.

OLIVER O. P. WILTERMOOD, OF MIDDLEPORT, WASHINGTON.

SEWER CLEANER.

Application filed November 28, 1919, Serial No. 341,069. Renewed April 12, 1922. Serial No. 555,239.

To all whom it may concern:

Be it known that I, OLIVER O. P. WILTERMOOD, a citizen of the United States, residing at Middleport, in the county of Stevens 5 and State of Washington, have invented new and useful Improvements in Sewer Cleaners, of which the following is a specification.

This invention relates to machines for cleaning sewers, catch basins and the like, 10 and has for an object the provision of a portable machine, which may be easily and quickly adjusted.

Another object of the invention is the provision of a device of this character, which 15 includes a conveyor capable of longitudinal movement to permit of an adjustment to different depths and which may be swung to a right angular position to facilitate its transportation from place to place.

20 Another object is the provision of a sewer, or catch basin, cleaning machine having an agitator, which breaks up the accumulation therein, so as to permit of its ready removal by means of conveyor buckets, when 25 it may be deposited in a suitable receptacle upon a surface.

Other objects and advantages of the invention will appear as the following description is read in connection with the 30 accompanying drawings.

In the drawings:

Figure 1 is a plan view of a machine embodying the present invention.

Figure 2 is a front elevation of the same.

35 Figure 3 is a side elevation.

Figure 4 is a bottom plan view.

Figure 5 is a horizontal section.

Figure 6 is an enlarged detail vertical section of Figure 3.

40 Referring in detail to the drawings, wherein like characters of reference denote corresponding parts, the invention comprises a frame, which is substantially U-shaped in plan and includes side bars 10 and an end bar 11. The ends of the frame opposite the end-bar 11 are connected by means of a shaft 12, which is mounted in bearings 13 at the end of the frame. This frame may be carried upon a truck, or other suitable 45 conveyance, and may support a suitable motor, as indicated at 14, or the power used for the operation of the machine may be taken from the driving motor of the vehicle.

50 55 Mounted for sliding pivotal movement upon the shaft 12, is a conveyor, which in-

cludes side bars 15 which are provided with elongated slots 16 therein, through which the shaft 12 passes. Mounted in bearings at each end of the bars 15, upon shafts 60 17, is a sprocket 18, these sprockets being connected by a chain 19, which also passes over a sprocket 20, mounted upon the shaft 12. The chain 17 carries scoops or buckets 21, which are guided in the bars 15 and a 65 rotary movement imparted to the shaft 12, will, through the sprocket 20, impart movement to the conveyor chain so as to raise and lower the buckets.

Mounted upon the shaft 12 adjacent each 70 of the side bars 10, is a beveled pinion 22, each of these pinions engaging a pinion 23, which is carried upon one end of a shaft 24, mounted in suitable bearings 25, carried by the frame. The opposite end of each of the 75 shafts 24 carry pinions 26, which engage pinions 27, mounted upon a shaft 28 disposed transversely of the frame. Also mounted on the shaft 28, is a sprocket 29, which is connected to a sprocket 30 by 80 means of a chain 31, the last named sprocket being carried by a shaft 32 mounted in bearings in the side bars 10 of the frame. This last named shaft is suitably belted to a shaft 33, which takes its power from the motor 14, 85 through the means of suitable belting.

Hingedly secured to each of the side bars 10 of the frame, as indicated at 34, is a standard 35, the latter being preferably formed of trussed metal, and being removably held 90 in a position at right angles to the frame by means of braces 36. The standard 35 is suitably connected to the side bars 15, which carry the conveyor, as indicated at 37, so that the said standard will support the 95 conveyor in an upright position, when desired, or will permit of its being swung downward to a position substantially parallel to the frame. A chute 38 carried by the upper end of the side bars 35 receives the 100 material dumped from the buckets for the purpose of conveying the said material to a suitable receptacle.

Mounted in bearings in the upper end of the standard 35, are rollers 39 and 39', 105 over which passes a cable 40, one end of the said cable being connected to the upper end of the bars 15 and the opposite end with a drum 41 mounted upon the shaft 41'. A suitable clutch 42 serves to control the movement of the drum. By this means the conveyor may be raised or lowered as desired 110

for the purpose of adjusting it to various depths, so that as the material within the catch basin decreases, the conveyor may be lowered accordingly.

5   Mounted in bearings 43 upon opposite sides of each of the bars 15 are shafts 44 carrying beveled pinions 45 and 46 which are adapted to engage alternately a mutilated beveled gear 47 mounted upon the 10 shaft 17, thereby operating pivot arms 48 secured to the lower end of the shafts 44. The arms 48 act as agitators to loosen the accumulation within the catch basin, so that it may be readily scooped up by the buckets 21 15 of the conveyor. These agitators are so connected that the oscillation of the shafts 44 will impart a sweeping movement to the arms 48, the said arms traveling for a predetermined distance in an arc of a circle, 20 when the mutilated bevel gear 47 will engage the opposite beveled pinion upon each of the shafts 44 and be moved in a reverse direction, the said shafts 44 continuing to rotate in the same direction.

25   From the foregoing description and the accompanying drawings, it will be seen that the invention provides means for quickly and easily removing the accumulated material from sewers, catch basins and the like, and 30 if desired, the machine may be encased in a suitable cover to prevent the escape of odors, due to the removal of the accumulation.

The invention is susceptible of various changes in its form, proportions and minor 35 details of construction and the right is herein reserved to make such changes as properly fall within the scope of the appended claims.

Having described the invention, what is claimed is:

40   1. A machine of the class described comprising a substantially U-shaped frame, a shaft mounted in suitable bearings at the open end of said frame, a conveyor extending below and carried by said shaft, a directing chute carried by said conveyor, means 45

mounted upon the frame for adjusting the conveyor and chute relative thereto, an agitator located at the bottom of said conveyor, beveled pinions mounted on said shaft aforesaid, a second shaft mounted in suitable 50 bearings on said frame, beveled pinions mounted on the second mentioned shaft, a plurality of shafts mounted in suitable bearings intermediate the first and second mentioned shafts and extending along said 55 frame, beveled pinions carried at opposite ends of said shafts and meshing with the beveled pinion carried by the first and second mentioned shafts, a sprocket wheel carried by the second mentioned shaft, a third 60 shaft mounted in suitable bearings on said frame, a sprocket wheel carried by the last mentioned shaft, an endless chain connecting said sprocket wheels, a drive shaft suitably belted to the last mentioned shaft, a 65 driving motor supported by the frame for actuating all of said shafts aforesaid and operating said conveyor and said agitator.

2. A machine of the class described comprising a substantially U-shaped frame, a 70 shaft mounted in suitable bearings at the open end of said frame, a conveyor mounted for sliding pivotal movement upon said shaft, a shaft mounted in suitable bearings at each end of said conveyor, a mutilated 75 gear carried by said shaft, a plurality of shafts mounted in suitable bearings upon opposite sides of said conveyor, beveled pinions carried by each of said shafts and adapted to engage alternately said mutilated gear, pivot 80 arms carried by the lower ends of said last mentioned shafts and adapted to travel for a predetermined distance in an arc of a circle, means mounted upon the frame for adjusting the conveyor relative to said frame 85 and means for operating said conveyor and pivot arms aforesaid.

In testimony whereof I affix my signature.

OLIVER O. P. WILTERMOOD.
